METHOD OF AND MEANS FOR REPAIRING
MASONRY STRUCTURES

Benjamin J. Many, Chicago, Ill.

Application September 15, 1937, Serial No. 164,074

6 Claims. (Cl. 72—107)

My invention relates to masonry structures, and has among its objects and advantages the provision of an improved method of and means for structurally rehabilitating and moisture-proofing such structures.

In many masonry structures, particularly in mass concrete work, leakages occur. The causes of such leakage are usually due to separation of the aggregates in the fabrication of the structure. In many cases the honey-combed or porous areas are visible on the exposed face of the concrete and may be patched when the forms are stripped. Such patch work is, of course, limited to the accessible face of the structure.

Oftentimes, one face of a mass concrete construction in the nature of a wall, bridge, and the like lies adjacent earth or other impediments which render that face of the structure inaccessible for treating or patching purposes. In many cases the porous or defective areas are located on the inaccessible face of the structure and are not visible from the accessible face. The infiltration of water together with the ground chemicals will eventually cause disintegrated areas to appear on the accessible face. It is a recognized fact that to properly repair such defective areas it is necessary to prevent the ingress of water from the inaccessible face of the structure.

In the past attempts have been made to drill a hole through the structure and then force grout or other material through the hole with a view to repairing the defective area. The treating material has been delivered through the opening under high and low pressures, but there is no assurance that the material will be properly applied to the desired area. Treating material delivered under pressure tends to flow in the direction of the pressure applied thereto, and after delivery to the opposite side of the wall, the material will follow the lines of least resistance. It frequently occurs that the obstruction on the inaccessible face of the wall includes large channels or openings through which the material flows and in some cases sewers have been blocked and damage caused to other adjacent installations.

An object of my invention is to provide a method of and means for repairing heretofore inaccessible areas in mass concrete construction.

Another object of my invention is to provide a novel back pressure method whereby treating material may be directly applied under pressure to the heretofore inaccessible face of the structure.

A further object is to provide a novel tool de-

signed to convey treating material through the wall under high pressure and in which the tool is so constructed as to deflect the treating material under pressure back upon the defective area.

In the accompanying drawing:

Fig. 1 is a sectional view of a masonry structure illustrating the manner in which the method is applied to an overhead structure for directly applying a treating material to a defective area adjacent an obstruction;

Fig. 2 is a sectional view of the masonry structure in the nature of a vertical wall lying adjacent an obstruction;

Fig. 3 is a sectional view of the material deflecting head of my conveyor;

Fig. 4 is a sectional view along the line 4—4 of Fig. 3; and

Fig. 5 is a diagrammatic view illustrating the manner in which large defective areas in the structure may be treated.

In the embodiment selected to illustrate my invention, Fig. 1 illustrates a masonry structure 10 having a disintegrated area 12 adjacent the obstruction 14 which is illustrated as constituting earth. The defective area may consist in deep surface pits or cavities 16. The structure illustrates interior cavities and fissures, as at 18 which, in turn, communicate with a seepage channel or crack 20, which frequently extends completely through the structure. Obviously, a disintegrated structure according to the illustration of Fig. 1 cannot be properly treated unless the treating material is directly applied to the defective area. To apply the material, I bore a hole 22 through the wall adjacent the seepage channel 20 or in line with the seepage channel. A pressure tool or conveyor 24 is inserted in the hole 22 and is so constructed at its end 26 as to forcibly deliver the treating material in a reverse direction directly against the defective area 12.

In practicing my invention I prefer to make use of a treating material consisting of a filler held in suspension by a liquid medium. Such material is of a fluid nature and may be effectively applied with an air gun or other equivalent devices well known in the art. The treating material embodies an element of penetration of such a nature as to penetrate the masonry structure to a depth greater than the normal penetration of moisture in the structure. When applied to leakage channels and the like, the material penetrates laterally of the defective area to a depth beyond normal penetration of moisture. At the same time, the leakage channels, surface

pits, cavities, and the like will be filled with a deposit of the filler. After application, the material sets into a firm homogeneous mass which not only moisture-proofs the structure but also

5 structurally rehabilitates the same.

The tool or conveyor 24 comprises a pipe 28, which includes a fitting 30. Fitting 30 is tubular and communicates with the pipe 28 and is provided with a conduit 32 for connection with the

10 compressed air system. A conduit 34 is connected with the fitting 30 for connection with the material supply. Such devices are well known in the art and need not be described in further detail.

15 One end of the pipe 28 is constricted at 36 and includes an exteriorally threaded shank 38 having threaded connection with a ring 40 which carries the deflecting head 42. The deflecting head is integrally connected in spaced relation

20 with the ring 40 through the medium of ribs 44. The outer end of the head 42 is curved, as at 46, to facilitate insertion through the hole 22. The inner face of the head 42 is concaved, as at 48, which concaved surface terminates in a conically-

25 shaped element 50 positioned centrally of the head with its axis corresponding to the axis of the pipe 28. Ring 40 also has an outer diameter not exceeding the outer diameter of the pipe 28 so that the head 42 and the ring 40 will pass 30 easily through the hole 22 with the pipe 28 fitting snugly therein.

Referring to Fig. 4, it will be noted that the ribs 50 are ovate in cross section with their major axes aligned radially of the pipe 28. The 35 concaved surface 48 is spaced sufficiently far from the end 52 of the pipe 28 and the ring 40 to provide clearance for the treating material delivered to the defective area 12. The constricted area 36 of the pipe 28 terminates in a curvature 40 54 while the ring 40 includes a curvature 56, both of which curvatures define a configuration substantially conforming to the shape of the concaved area 48, thus permitting free flow of the laterally and backwardly deflected material.

45 In operation, the pipe 28 is pushed into the hole 22 sufficiently far to bring the end 52 in alignment with or slightly beyond the face of the wall structure to be treated. Upon the pipe 28 I mount an adjustable collar 58 arranged to engage the face 60 of the structure 10 for precisely positioning the head 42 in proper relation with the opposite face of the structure 10. The collar 58 may be adjusted to different positions and secured in position by a bolt 62. The thickness of the wall is calculated and the collar 58 adjusted to the proper location and then made secure. After proper adjustment of the collar, the pipe 28 is merely pushed through the hole 22 until the collar 58 engages the face 60.

50 After the pipe 28 has been positioned as illustrated in Fig. 1, the material and compressed air is admitted to the pipe through the medium of any suitable means, not illustrated, and which forms no part of the present invention. Such valve controls are well known in the art and need not be described.

Because of the fluid nature of the treating material and the high pressure employed, which frequently ranges between 350 and 500 pounds per 70 square inch, the material will be discharged forcibly against the concaved face 48 and deflected laterally and backwardly. The spread of the deflected material depends upon the curvature of the concaved face 48. With the head 42 positioned according to Fig. 1, the treating material

will be discharged laterally over a sufficient area to cover the defective area 12. The high pressure employed insures application of the treating material by force directly to the impaired area.

The treating material will fill the pits or cavities 14 and 18 as well as the seepage channel 20. Because of the penetrating properties of the treating material, deep penetration is attained, as indicated at 64, while the cavities and seepage channels will be completely filled with a body material, as indicated at 66. Thus, in deeply impregnating the areas contacted by the treating material as well as filling the seepage channels and cavities with a body material, I prevent any circumvention of moisture around the treated area. After application, the treating material sets into a firm mass, thereby not only moisture-proofing the structure but also structurally rehabilitating the same so as to render the structure intact.

While Fig. 3 illustrates the head 42 having a concaved area 48 of a given configuration, the head 42 is so designed as to be readily disconnected from the pipe 28 to permit substitution of other heads 42 of differently shaped concaved faces. Thus, the spread of the material may be determined by substituting a head 42 of a given concavity. In narrowing the ribs 44 in the manner illustrated in Fig. 4, little resistance is offered to the laterally moving material. In operation, the concaved face 48 will, in fact, deflect the treating material over the entire surface within a circular area depending upon the degree of curvature.

In applying treating material by the back pressure method illustrated, I entirely eliminate excessive waste in addition to providing a system whereby the treating material is directly and forcibly applied to the area to be treated.

Fig. 2 illustrates the same back pressure system applied to a vertical masonry structure in which the obstruction is indicated at 67. The masonry structure 68 is bored at 70 for receiving the pipe 28 with its head 42 positioned in the same manner as in connection with Fig. 1. The structure 68 includes a transverse seepage channel or crack 72. In both Figs. 1 and 2, it will be noted that the obstructions 14 and 67 are washed out at 74.

In many cases the cavities 74 are of large proportions, and it frequently happens that such cavities communicate with channels or other cavities. Under such conditions the old method of treatment, which consisted in forcibly delivering treating material through the hole in the wall, the material will take the path of least resistance with no assurance that any of the treating material would reach the defective area. Under such conditions the treating material is wasted, the building structure is not repaired, and there have been cases where sewers have been blocked and damage caused to other adjacent structures.

In my method, whether considered under the structural conditions of Fig. 1 or 2, the head 42 will forcibly deflect the treating material over the defective area so as to moisture-proof and structurally rehabilitate the entire area within the range of the head. If the defective area is of large proportions, as indicated at 76 in Fig. 5, a number of holes 22 may be drilled and the tool shifted from hole to hole to apply the material over the entire area 76. After treating the defective area, the tool is removed and the hole or holes plugged.

Without further elaboration, the foregoing will so fully explain my invention that others may, by applying current knowledge, readily adapt the

same for use under various conditions of service.

I claim:

1. The method of treating masonry structures having an outer face and an inner face, which 5 consists in boring a hole through the masonry structure inwardly of its outer face, inserting a treating material conveyor in said hole, and conveying treating material through the conveyor and deflecting the treating material back upon 10 a predetermined area on said inner face circumjacent said hole.

2. The method of treating masonry structures having an outer face and an inner face, which 15 consists in boring a hole through the structure inwardly of its outer face, inserting a material conveyer through the hole and deflecting the material directly and forcibly back upon a predetermined area of said inner face circumjacent 20 said hole.

3. A device of the type described comprising a fluid material conveying tube, a deflecting element attached to one end of the tube in spaced relation therewith, said deflecting element having a concaved face axially aligned with the tube for deflecting fluid treating material laterally and in 25 all directions of the tube and reversely of its movement therethrough.

4. A device of the type described comprising a fluid treating material conveying tube, a fluid treating material deflecting head, means for detachably connecting the fluid treating material 30

deflecting head with the tube, said fluid treating material deflecting head being arranged in axial alignment with the tube and having a concaved face for deflecting the fluid treating material laterally in all directions and reversely of its flow 5 through the tube.

5. The method of treating masonry structures having an outer face and an inner face, which 10 consists in providing an opening through the structure inwardly of its outer face, positioning material deflecting means in axial alignment with said opening a predetermined distance beyond 15 said inner face, and conveying fluid treating material forcibly through said opening and impinging the same against said deflecting means to deflect the treating material upon a predetermined area on the inner face circumjacent said opening.

6. The method of treating masonry structures having an outer face and an inner face, which 20 consists in providing an opening through the structure inwardly of its outer face, inserting a fluid material conveyor having a material deflector in said opening, with the material deflector positioned in axial alignment with said opening a 25 predetermined distance beyond said inner face, and forcibly passing treating material through said conveyor into impinging relation with said deflector for deflecting the treating material back upon the inner face circumjacent said opening. 30
